DAVID A. HILDEBRAND, OF OAKLAND, CALIFORNIA

BUILT-IN TABLE

Application filed February 3, 1930. Serial No. 425,526.

The invention is for a built-in table.

Modern homes are at present equipped with many built-in conveniences, and the purpose of the invention is to provide a built-in table which may be extended at will, and which, when not in use, may be disposed within the wall or one of the cabinets and which in such a case will replace one of the drawers in such cabinet, and have the same appearance as a drawer. Therefore, to provide for storage in a comparatively shallow space, a roll top is provided, which passing over a roller in the wall or cabinet hangs downward when the table is closed. As this type of table does not permit of legs or knee braces, telescopic supporting members form a part of the device, which members telescope relative to each other, and as the supporting members are being telescoped, the roll top passes over a roller in the wall and depends therefrom. The front panel or connecting member between the supporting members is made to suit the surrounding trim or cabinet. Should the device be installed in a comparatively shallow wall, the telescoped supporting members could readily be folded upward into the wall by pivoting the members adjacent the roll, on the roll supporting shaft or pins. In either case the table, when telescoped, could readily be made to form flush with the surrounding walls or cabinet.

The main object of the invention then, is to provide a telescopic table, as a built-in feature for the modern home.

Another object of the invention is to provide a device as described which may be installed in any home or building and in such a location as to offer the greatest convenience, and of such area or size as may be desired.

A further object of the invention is to provide a device as described which is conveniently operated, and which when folded or telescoped will be in harmony with the surrounding woodwork or trim, and which may be installed in a wall, or any cabinet as may be desired.

Further objects of the invention will become apparent as the description is set forth, and from the accompanying drawing, in which:

Fig. 1 is a perspective view of the invention in extended position and ready for use;

Fig. 2 is a sectional elevation through a wall and showing the table closed, and the table top suspended from the roller, hanging in the wall space;

Fig. 3 indicates the assembly of the telescopic supporting members in plan, as also the roller and its supporting members, top removed;

Fig. 4 is a sectional longitudinal elevation taken through the roll top and front panel, and indicating the stops on the telescopic supporting members; and

Fig. 5 indicates a transverse section through the telescopic supporting members.

Similar reference characters are used throughout the several views to indicate similar parts.

The invention consists primarily of two series of telescopic members constituting supporting elements, a cross member rigidly connecting the farthest extensible members, stops for excess extension of the telescopic members, a roll type top attached only to the farthest extensible telescopic members, and a roller disposed in the wall over which the top is adapted to roll when the supporting members are being telescoped, the top hanging downward from the roll when the table is closed.

The roll top 7 may consist of any of the well known roll materials such as is used for roll top desks, doors and curtains and of any rigid material, but is preferably made as indicated in Fig. 4, which consists of a multiplicity of narrow wood strips 8, each strip 8 provided with an arcuately formed tongue 9 on one side thereof and an arcuately formed groove 10 on the opposite side thereof, perpendicular faces 11 extending from the tongue and groove to the top surface 12. The bottom surface 13 of each strip is narrower than the top surface 12 so as to cause the faces 11 to contact when the table is extended, thereby forming a continuous surface. Attached to the bottom 13 of the strips 8 are continuous strips of flexible material 14, such as canvas or other fabric material, forming a continuous section of strips 8, and

sufficiently flexible to pass over a roller 15 with the side 13 adjacent. The roller 15 may be constructed of any suitable material and pivotally mounted between supporting members 16.

The supporting member comprises a plurality of telescopic members 17 in overlapping relation and provided with interlocking, slideable tongue and groove 18 and 19 forming a rigid support when extended. A groove 20 at the base of groove 19 and centrally disposed, terminating adjacent the forward end of the telescopic members 17 provides a stop shoulder to coact with a stop pin 21 passing through the cooperating telescopic member. The farthest extensible telescopic support members 22 have rigidly attached thereto in spaced relation, a panel 23, adapted to close the opening 24 when the table is closed. The main support members, into which the first member 17 slides may be fixed to members 16 or may rest on the frame 26 and pivoted on the roll pivots 27. A knob or handle 28 is provided on panel 23 for convenience of operation.

The operation of the device merely requires drawing the table out as desired, and as indicated in Fig. 1, and when no immediate further use of the table is desired, it is pushed back into the wall as indicated in Fig. 2.

Having described an operative method of constructing, installing and using the device, it will be understood that such variations in design, construction and arrangement of parts may be resorted to, as prove to be consistent with the scope and spirit of the appended claims.

I claim:

1. A roll top presenting a continuous unbroken surface when extended and comprising a multiplicity of narrow rigid strips transversely disposed and attached on the under side thereof to strips of flexible material extending throughout the length of said top, said narrow rigid strips being of substantially equal height and width and provided with perpendicular contact sides adjacent the top thereof, an approximately centrally disposed arcuate groove on one side thereof and a cooperating arcuately formed tongue on the opposite side thereof, the width of said strips being greater at the top surface than at the bottom surface.

2. A roll top comprising a multiplicity of long rigid members of substantially small cross section, transversely disposed and attached at the bottoms thereof to strips of canvas or other flexible material, the tops of said long rigid members being of substantially greater width than the bottoms thereof, contacting side faces adjacent the tops thereof, cooperating arcuately formed tongues and grooves on the opposite sides thereof, said top forming a continuous un-

broken surface when disposed in parallel relation throughout.

3. A flexible table top comprising a plurality of substantially long rigid members of substantially small cross-sectional area, transversely disposed, the bottom surfaces thereof being secured to strips or webs of flexible material, the top and bottom surfaces of said strips being plane and parallel, the upper side surfaces being in apposition, the lower side surfaces spaced apart and the intermediate portion rockably related.

4. A flexible table top comprising a plurality of flexible webs, a plurality of rigid members transversely disposed and having the bottom surfaces affixed to said webs, each of said rigid members consisting of a strip of wood having plane top and bottom surfaces parallel one to the other, the sides being respectively formed with an intermediately disposed semi-circular tongue and cooperating groove, the side faces being perpendicular to said upper and lower surfaces, the width of said strip being less below than above said tongue and groove.

In testimony whereof I have affixed my signature.

DAVID A. HILDEBRAND.
